ELECTRIC FENCE INDICATOR

Carl Pfanstiehl, Highland Park, Ill.; Caryl Cody Pfanstiehl, executrix of Carl Pfanstiehl, deceased, assignor to Babson Bros. Co., Chicago, Ill., a corporation of Illinois

Application October 23, 1940, Serial No. 362,455

3 Claims. (Cl. 177—311)

This invention relates to an electric fence indicator, and more particularly to means for determining the true effectiveness of an electric fence in its function of stopping and holding cattle or other animals.

One feature of this invention is that it provides improved means for indicating the true effectiveness of a normally open circuit electric fence; another feature of this invention is that the indication is a true reflection of the effectiveness of the fence, despite various changes in its conditions; a further feature of this invention is that the indicating means is very simple, rugged, and easily manufactured and used; other features and advantages of this invention will be apparent from the following specification and the drawing, in which:

Figure 1 is a front elevation of an electric fence controller or energizing device embodying my invention; Figure 2 is a fragmentary elevation of the means providing a visual indication of the effectiveness of the fence; and Figure 3 is a schematic diagram of apparatus embodying my invention.

This present application is a continuation-in-part of my earlier application, Serial No. 243,244 filed November 30, 1938, and entitled "Signal device for an electric fence," which application was a divisional of my earlier application Serial No. 238,914, filed November 9, 1938, entitled "Electric fence," which issued July 15, 1941, as Patent No. 2,249,696, and is more particularly directed to a transformer for providing a plurality of voltages.

Electric fences are intended to stop and hold animals by electric shocks, rather than by their mechanical strength, the shock used being strong enough to cause the animal to avoid the fence but not strong enough to permanently injure the animal or anyone accidentally coming in contact with the fence. In order to insure safety of such fences it has been determined that the maximum current deliverable to the fence should not exceed twenty-five milliamperes, and current flow should be intermittent, current being supplied to the fence wire not more than one-tenth second and about once a second. State and other codes have incorporated these and similar requirements, and electric fences now sold normally incorporate a circuit interrupter in the primary designed to close the circuit for less than one-tenth second approximately once each second; and some means is included to limit the output current to twenty-five milliamperes.

Inasmuch as an electric fence normally com-

prises only a single fence wire, and since this fence wire is sometimes strung for a distance of several miles, it is highly desirable to provide an indication at the controller or energizing apparatus to indicate whether the fence is operative. Original indicators employed merely showed whether or not any current was reaching the fence at the desired intervals, as by placing a small filament lamp in series with the fence; more recent indicators have in some cases endeavored to reflect the condition of the fence, so that the farmer may know whether it is effective to hold his cattle. Such fences are generally strung from insulators from fence posts, and trouble with poor insulation is frequently encountered; moreover, weeds frequently grow into contact with the fence wire and provide a partial ground of varying degree, this same type of ground being encountered from bushes or leaves where the fence is strung through woodland, along a creek bank, or the like. Heretofore efforts to indicate the effectiveness of the fence, so far as I know, have merely measured the current being delivered to the fence, and have assumed that if a high current was being delivered to the fence when no animal was in contact with it that the fence was in poor condition and relatively ineffective.

I have found, however, that other conditions of the fence render such a method a poor indication of the true effectiveness of the fence in stopping animals. Variations in fence length and height from the ground, for example, cause variations in the fence-to-ground capacity. A large capacity, as that of three or four miles of fence wire, may cause a considerable charging current to flow into the fence each time the secondary of the transformer in the controller is energized even though the fence is in optimum condition. Moreover, capacities which happen to cause resonance conditions with the secondary of the transformer, or an approach to such conditions, frequently cause abnormal currents to flow in the fence wire even though the phase conditions are such that there is little or no power loss, and the fence is in good condition and highly effective. I have found that the best indication of the true effectiveness of the fence for its desired function is the voltage existing between the fence wire and ground upon each energization; and I am here disclosing a simple, rugged and effective means for indicating the effectiveness of the fence as a function of such voltage.

In the particular embodiment of my invention

illustrated herewith a casing 10 adapted to be hung on the wall of a barn or the like encloses the operative parts for energizing the fence from a conventional commercial source of current, manually rotatable elements 11 and 12 being provided for purposes to be hereinafter more fully described. A glass bull's-eye or similar means 13 enables the condition of a neon or similar glow tube to be seen; and the make and break mercury switch 14 is also visible from the front of the casing.

Turning now more particularly to the schematic diagram of Figure 3, it will be seen that the source of conventional current, as 110 volts A. C., is supplied by the two wires 15 and 16 to a small motor 17, preferably of synchronous type, and to the primary 18 of a transformer, the circuit through the primary being completed through the mercury make and break switch 14. The mercury switch is mounted to be rocked back and forth by the lever 19, which is oscillated by a crank arm or eccentric 20 driven through a gear train by the motor 17. Each time the mercury switch is rocked from one side to the other the small drop 21 of mercury touches the two contacts in passing and completes the circuit through the primary 18 of the transformer. This energization of the primary is very brief, however, being less than one-tenth of a second; and the gearing and rate of rotation of the motor 17 is such that the contact is made approximately once each second.

The secondary 22 of the transformer is here shown as having its upper end connected by the lead wire 23 to a fence wire 24 supported by the posts 25. It is understood that this fence wire is normally insulated from ground in approved manner, as by supporting it from the fence posts by porcelain or similar insulators. The bottom end of the secondary 22 is connected to ground by the wire 26, so that any voltage developed across the secondary 22 is applied between the fence wire 24 and ground, and causes a shock to any animal contacting the fence and completing the circuit to ground.

The transformer is of the step-up type, preferably raising the voltage to somewhere between one thousand and two thousand volts open circuit. In a commercial embodiment of my invention (fully illustrated and described in my above mentioned Patent No. 2,249,696) a tapped secondary transformer is used providing a plurality of secondary voltages, as more fully explained in one of my above-mentioned applications; but for simplicity I here show only one voltage condition, which may be considered to correspond to the setting of the switch 12. The transformer is, of course, of the type which is self-limiting as to maximum current deliverable, this being accomplished by a central shunt path provided by the leg 27 of the transformer.

Since the voltage applied to the fence is normally quite high, I employ means for providing an indicating voltage bearing a predetermined ratio to the total voltage across the secondary of the transformer. While this could be done in any desired manner, as by an additional secondary, a potentiometer, or the like, I here employ a portion of the secondary 22 as a subsidiary secondary 28, tapping off a desired number of turns from the bottom of the secondary 22 with the wire 29. This wire is connected through a fixed resistance 30, a wire 31, and the variable resistance 32 to the wire 26, so that the fixed and variable resistances are connected in series to be

energized by the subsidiary secondary 28. I have employed a sufficient number of turns in the subsidiary secondary to provide 150 volts on open circuit when the entire secondary 22 is providing 780 volts on open circuit, for example; and have used a 6,000 ohm resistor for the fixed resistance 30 and a 15,000 ohm to zero variable resistance corresponding to the variable resistance 32. The manually rotatable indicator 11 operates the variable resistance 32, the full 15,000 ohms being in circuit when the pointer is clear to the left of its swing and no resistance being in circuit when the pointer is clear to the right of its swing.

In shunt with the variable resistor 32 is a glow lamp 33. While this may be of any type employing vapor or inert gas and activated at a predetermined voltage, I find conventional neon tubes or glow lamps very acceptable. The one which has been employed in a commercial embodiment of this invention has a break-down voltage of 46 volts. Such lamps can be obtained on the market quite cheaply, and their breakdown voltage stays within fairly close limits. It will be readily seen that the voltage developed across the plates or elements of the glow lamp 33 is a function of the voltage across the variable resistance 32, which is in turn a function both of its setting and of the voltage being developed in the subsidiary secondary 28. If the subsidiary secondary is delivering 150 volts and the variable resistance 32 is set at 3,000 ohms one third of this voltage or fifty volts would be developed across the variable resistance, and thus this voltage would be developed across the lamp at such resistance setting. The indicator arrangement is such that a setting of 3,000 ohms in the variable resistance 32 would cause the pointer to lie in the range labeled "Good" on the face plate, a portion of which is shown in Figure 2. On the other hand, if a partial short on the fence caused a reduction in the fence to ground voltage upon each energization, this would be reflected in the subsidiary secondary. If it be assumed that the voltage was cut in half, the subsidiary secondary would only develop 75 volts across it and the variable resistance 32 would have to exceed about 12,000 ohms in order to cause the lamp 33 to light. This would cause the indicator to be way over to the left end of the scale, in the weak to fair range, almost in the position shown in Figure 2.

It will thus be seen that an indication of the true fence to ground voltage, and thus the effectiveness of the fence, can be determined at any time by turning the indicator 11 slowly until a change in state of the light occurs. That is, if the indicator is started at the left or weak side and turned to the right, the light would stay on until a certain position was reached and then would not light, since there would not be sufficient voltage developed across the variable resistance 32 to equal the break-down voltage of the glow lamp 33. The pointer would then show whether the condition of the fence was weak, fair, good, or the like. The process could, of course, be reversed, and the indicator started from the righthand end of its swing and turned slowly until the light just lit, the results being the same in either case.

While I have described certain embodiments of my invention, it is to be understood that it is capable of many modifications. Changes, therefore, in the construction and arrangement may be made without departing from the spirit and

scope of the invention as disclosed in the appended claims.

I claim:

1. Means for indicating the effectiveness of an electric fence comprising a bare fence wire connected to energizing means adapted to provide a predetermined open-circuit voltage, including: means electrically coupled to the energizing means for providing an indicating voltage bearing a predetermined ratio to the voltage on the fence; a glow lamp adapted to be energized by the indicating voltage; and manually operable means for varying the voltage applied to the glow lamp, said last mentioned means including indicating means.

2. Means for indicating the effectiveness of an electric fence comprising a bare fence wire connected to the secondary of a transformer having its primary suitably energized and adapted to provide at least one predetermined open-circuit voltage to the fence wire, including: means electrically coupled to the transformer for providing an indicating voltage bearing a predetermined ratio to the voltage on the fence; a glow lamp

5 adapted to be energized by the indicating voltage; and manually operable means for varying the percentage of the indicating voltage applied to the glow lamp, said last mentioned means including indicating means calibrated in fence effectiveness.

10 3. Means for indicating the effectiveness of an electric fence comprising a bare fence wire connected through voltage varying means to the secondary of a transformer having its primary suitably energized, the voltage varying means being adapted to provide a predetermined open circuit test voltage at one setting, including: means electrically coupled to the transformer for providing an indicating voltage bearing a predetermined ratio to the voltage on the fence; a glow lamp adapted to be energized by the indicating voltage; and manually operable means for varying the percentage of the indicating voltage applied to the glow lamp, said last mentioned means including indicating means calibrated in fence effectiveness.
